CLAIM

(57) The ornamental design for a fill cap for a drink container, as shown and described.

DESCRIPTION

FIG. 1 is a perspective view of a fill cap for a drink container showing our new design;

FIG. 2 is a front elevational view thereof;

FIG. 3 is a bottom plan view thereof;

FIG. 4 is a top plan view thereof;

FIG. 5 is a cross-sectional view thereof taken along line 5-5 in FIG. 4;

FIG. 6 is a cross-sectional view thereof taken along line 6-6 in FIG. 4; and,

FIG. 7 is a cross-sectional view thereof taken along line 6-6 in FIG. 4, and shown in use on a container.

The rear, left side and right side elevational views are identical with the front elevational view.

The broken lines in FIG. 7 illustrate environmental structure and form no part of the claimed design.
